RANCH PLIERS

William E. Seger, Los Angeles, Calif.

Application May 28, 1951, Serial No. 228,676

1 Claim. (Cl. 254—77)

1

This invention relates to combination tools. An object of this invention is to provide a combination tool known as a ranch pliers which is designed for use in setting up and repairing wire fences particularly barbed wire fences.

Another object of this invention is to provide a combination tool which is so constructed and arranged that the broken ends of wire may be drawn together and the wire on the fence tightened.

A further object of this invention is to provide a combination tool of this kind which will speed up the repair of installation of wire fences or the like.

With the above and other objects in view, my invention consists in the arrangement, combination and details of construction disclosed in the drawings and specification, and then more particularly pointed out in the appended claim.

In the drawings:

Figure 1 is a detailed side elevation of a combination tool constructed according to an embodiment of this invention.

Figure 2 is a bottom plan view of the tool.

Figure 3 is a front elevation of the tool showing the manner in which a pair of broken ends are drawn together and the wire tightened.

Figure 4 is a sectional view taken on the line 4—4 of Figure 1.

Figure 5 is a sectional view taken on the line 5—5 of Figure 1.

Referring to the drawing, the numerals 10 and 11 designate generally a pair of elongated handles which are pivotally connected together at their forward ends by means of a pivot 12. The handle 10 at the rear thereof is formed with an opening 13 and the handle 11 is also formed with an opening 14 at the rear thereof. The openings 13 and 14 are adapted to be disposed in registry when the handles 10 and 11 are in closed position, and a pin or like element is adapted to be inserted through the registering openings 13 and 14 so as to hold the handles 10 and 11 against rocking movement relative to each other.

The pivot 12 at one end thereof extends laterally of the forward end of the handle 11 and is provided with a grooved wire tightening member 15. The handle member 11 has extending from the forward end thereof a jaw 16 which is formed on the lower side thereof with a cam surface 17. The handle member 10 has extending from the forward end thereof a jaw 18 which confronts the jaw 16 and a hammer head 19 projects from the jaw 18 and is provided at the rear thereof with a hook 20 by means of which staples or the like may be removed.

2

The jaw member 16 is provided with a wire cutting blade 21, and the jaw member 18 is provided with a complementary wire cutting blade 22. The jaw member 18 is formed with a wire gripping or clamping jaw 23 confronting a wire gripping or clamping jaw 24 which is carried by the jaw member 16 so that when a wire is cut by engagement between the blades 21 and 22, the wire disposed between the jaws 23 and 24 may be tightly gripped. The jaw member 18 is formed with a toothed or serrated inner side 25 confronting a smooth jaw surface 26 carried by the inner side of the jaw member 16.

In order to provide a means whereby a wire such as a fence wire may be tightened, the jaw member 18 is provided on the inner side thereof forwardly of the serrations 25 with a transversely disposed notch 27, and the jaw member 18 is also provided on the outer side thereof slightly rearwardly of the notch 27 with a second notch 28. A third notch 27a is also provided on the inner side of jaw 18 parallel to notch 27 and spaced rearwardly of notch 28. Notch 28 is thus offset from notches 27 and 27a in a direction parallel to a line joining notches 27 and 27a. A U-shaped wire tightening or winding member 29 which is commonly termed a staple is adapted to be engaged within the notches 27 and 28 as shown in Figure 3 with the free or open ends of the staple or tightening member 29 extending laterally from one side of the jaws 16 and 18.

In the tightening of a broken wire one end 30 of the wire is extended from one direction under and over the two sides of the staple 29, and the other end 31 is extended from the opposite direction over and under the sides of the staples 29. The jaw member 16 at the forward end thereof is provided with a pair of inwardly curved jaws 32 which form a longitudinally disposed channel or notch 33 within which the head of a nail is adapted to be engaged where the device is used in pulling a nail.

The forward end of the handle 11 is provided with a shoulder 34 which constitutes a stop means for limiting the rocking of the two handles relative to each other when these handles are rocked to a jaw opening position.

In the use of this device where it is desired to tighten a strand of wire the wire may be engaged with the grooved wire tightening pin or head 15 and the tool then rocked with the forward end thereof as a fulcrum. In the event it is desired to tighten the wire to a degree which cannot be tightened by the use of the grooved member 15 the wire may be threaded either in its broken or unbroken condition through the

parallel sides of the staple 29 which at this time is engaged and clamped within the notches 27 and 28 of jaw member 18.

The tool is then rotated or swung to a circle with the staple 29 as a pivot so that the wire ends or the unbroken wire will be wound upon the parallel sides of the staple or wire tightening member 29.

The tool hereinbefore described provides a combination tool which is capable of performing 10 all of the operations required in the mounting of wire to form a fence, the repair of the wire or the tightening of the wire.

What is claimed is:

A ranch pliers comprising a pair of pivotally 15 connected together handles, a pair of opposed jaws having confronting faces extending from said handles, one of said jaws having a pair of transverse notches arcuate in cross section, on the confronting face thereof and a third trans- 20 verse notch, arcuate in cross section, on the opposite non-confronting face thereof, said third notch being offset from each of the other two notches in a direction parallel to a line joining

4
said other two notches, whereby a U-shaped wire tightening staple may be disposed in and engaged by said third notch and one of said pair of notches to project laterally of said jaws, and a lip on the other of said jaws to clampingly hold said staple in one of said pair of notches between said confronting jaws, said other jaw having a smooth confronting face.
